UNITED STATES PATENT OFFICE

133,508

DESIGN FOR A JACKET

Leon Leventhal, New York, N. Y.

Application July 27, 1942, Serial No. 107,713

Term of patent 3½ years

To all whom it may concern:

Be it known that I, Leon Leventhal, a citizen of the United States, residing in New York city, in the county of New York and State of New York, have invented a new, original, and ornamental Design for a Jacket, of which the following is a specification, reference being had to the accompanying drawing, forming part thereof.

Fig. 1 is a front view of a jacket showing my new design, and

Fig. 2 is a rear view of the jacket shown in Fig. 1, and

Fig. 3 is an enlarged fragmentary view of the jacket shown in Figure 1 with the collar in raised position.

I claim:

The ornamental design for a jacket, substantially as shown.

LEON LEVENTHAL.
